UNITED STATES PATENT OFFICE

ERNEST R. ERICKSON, OF DES MOINES, IOWA, ASSIGNOR TO C. E. ERICKSON COMPANY, INC., OF DES MOINES, IOWA

DESIGN FOR AN OIL-METER CASING

Application filed April 24, 1930. Serial No. 35,371. Term of patent 7 years.

To all whom it may concern:

Be it known that I, ERNEST R. ERICKSON, a citizen of the United States, and a resident of Des Moines, in the county of Polk and State of Iowa, have invented a certain new, original, and ornamental Design for an Oil-Meter Casing, of which the following is a specification, reference being had to the ac-

companying drawing, forming part thereof.

The figure is a perspective view of the oil meter casing embodying my design.

I claim:

The ornamental design for an oil meter casing, as shown.

Des Moines, Iowa, April 8, 1930.

ERNEST R. ERICKSON.
